UNITED STATES PATENT OFFICE

2,305,632

SHORTING DEVICE

Nathaniel N. Okun, Bronx, N. Y., assignor of one-third to Charles M. Palmer, Washington, D. C.

Application July 1, 1940, Serial No. 343,496

7 Claims. (Cl. 172—279)

The invention is concerned with short circuiting means for repulsion induction electric motors and specifically is directed to a short circuiting device comprising an annular band of pivoted and radially disposed electrically conducting members or slugs normally held out of contact with the bars of the commutator of the motor during starting thereof to allow the motor to start on repulsion and after a certain predetermined speed is reached the outer portions of the swingable members are swung by centrifugal force to short or engage the commutator bars to permit the motor to operate inductively, this application being a continuation-in-part of my previous application Serial No. 133,556, filed March 29, 1937, now materialized into Patent No. 2,206,045. The objects, advantages, the improved and salient functional and structural features of the invention will be more readily understood from the teachings of the following description considered in the light of the accompanying drawing wherein:

Fig. 1 is a sectional view of the shorting device according to the invention illustrating the pivoted slugs thereof normally held out of contact with the commutator bars by a spiral spring.

Fig. 2 is a sectional view on the line 2—2 of Fig. 1.

Fig. 3 is a fragmentary view of Fig. 1 showing the swingable slugs held in contact with the commutator bars due to centrifugal force and against the resistance of the spiral spring.

Fig. 4 is a modified and fragmentary view of Fig. 1.

Fig. 5 is a view similar to Fig. 1 but illustrating modified spring means for normally holding the slugs out of contact with the commutator.

Fig. 6 is a fragmentary view taken on the line 6—6 of Fig. 5, and

Fig. 7 is a view similar to Fig. 6 but illustrating a modification.

According to Figs. 1-3 inclusive the short circuiting device comprises the insulating cup shaped annular shell or casing 13 having a marginal but annular hollow bead 35 defining an inner annular but enlarged channel or groove 36 in which enlarged heads 37 of the annular band of electrically conducting slugs 21 are swingably disposed. These slugs are provided with intermediate attenuated portions 38 terminating in hollow eyes 39 pivotally mounted on the fulcrum ring 40 disposed in the inner annular channel or groove 41 of the bushing or hub 42 of the insulating shell 13.

The intermediate attenuated portions 38 of

each of the slugs 21 are each provided with a recessed or concentric groove 44 adapted to cooperate with the annular inwardly overhanging stop rib 45 to limit displacement of heads 37 of the slugs when the motor is moving to a stopping position at which time lips 46 of the slugs retract or move away from the commutator bars 12 by reason of the outward thrust applied to the annular electrically conducting channeled copper shoe 47 which is continuously urged against flat faces 48 of the intermediate attenuated portions 38 of the slugs 21 by the spiral or tapered spring 49 having its outer and largest convolution 50 disposed and retained in an annular channel of the conducting shoe 47 while the inner contracted convolution 51 abuts the inner contracted end 52 of the tapered recess or cavity 53 in commutator support 11. The contracted end of spring 49 also abuts the motor shaft 10 and thus is firmly held in place.

With the motor at rest or moving to a stop position the floating copper annular shoe 47 holds the slugs out of contact with the commutator bars 12. In starting from a stop position and after a predetermined speed of the motor shaft has been reached, the centrifugal force imparted to the slugs overcomes the resistance offered by the helicoidal spring 49 and hence lips 46 contact or short the commutator bars until such time that the speed falls below the predetermined speed. Furthermore since the heads of the slugs have considerable mass, the momentum thereof rapidly increases or decreases depending upon the variations in speed and it follows that the slugs are readily responsive and therefore are positive and rapid in operation, that is, engage or disengage the commutator bars when required and promptly.

In the form according to Fig. 4 the annular groove 41 in which the tail portions or eyes 39 are pivotally or rotatably mounted is also characterized by the annular insulating beaded ring 60 secured to the hub of the shell by rivets 61. By the present arrangement the annular band 45 of swingable slugs during assembly may be mounted in the shell 13 in the advance of positioning the beaded ring on the annular hub 42. In other aspects the form according to Fig. 4 is along the lines illustrated in Figs. 1-3.

With the form according to Figs. 5 and 6 an annular sheet metal spring spider 65 has its radially extending and crimped but arcuate fingers 66 engaging the floating annular shoe 47 thus resiliently holding slugs 21 normally away from the commutator bars. Spider 65 however has its

lower hub portion fixedly retained on the motor shaft 10 and against the commutator support 11 by the annular spacer 68 positioned against the beaded ring 69 having its annular bushing 70 fixedly held on hub 42 and the bushing 70 closely fits shaft 10 and is retained against spacer 68 by the snap ring 73, the bead portion 71 of the ring 69 characterizes means to rotatably retain the enlarged rounded portions of the slugs 21 in the annular channel 41. By this arrangement the fulcrum ring 40 shown in Figs. 1-4 have been eliminated and the enlarged tail portions need not be perforated. In other aspects the embodiment shown in Figs. 5 and 6 is along the lines illustrated in Figs. 1-3.

In Fig. 7, shell 35 is of metal and is spaced from the commutator bars 12 and has its annular bead 13' characterizing a hub which has an annular bushing 74 firmly retained on the reduced portion 75 of the shaft against the spring spider 65 which is firmly held against the annular shoulder 76 of the shaft by the anchored snap ring 73. The substantially disc shaped or bulbous tails 72 of the swingable slugs 21 are rotatably confined in the annular channel 41 of bead or bearing 13' by the semi-spherical metal hollow ring 77 having its inner end 78 soldered at 79 to the bushing 74. In other respects the form illustrated in Fig. 7 follows the embodiment shown in Figs. 5 and 6 or in Figs. 1-4 wherein the snap ring holds the insulating shell 35 to position the end of its bead 35 in seal tight relation against the commutator. Thus in all of the forms disclosed a floating copper ring or shoe 47 is acted upon by spring means to hold the slugs 21 away from the commutator until a predetermined speed is reached and until the centrifugal force overcomes the resistance of the arcuate spring fingers 66 of the relatively thin spider 65 (Figs. 5-7) or overcomes the resistance of helical spring 51 (Figs. 1-4). At or above the predetermined speed, lips 46 which have a width coextensive with the width of the substantially disc shaped or bulbous heads 37, short the bars 12 until the speed drops below the predetermined speed at which time and until stopping of the motor the slugs are urged to their normal and fully retracted position by the spring means.

Various changes may be made in details of construction and arrangement of parts without departing from the spirit of the invention or sacrificing any of the advantages thereof inherent therein.

I claim:

1. In a short circuiting device for a motor commutator, an annular shell adapted to be mounted on the shaft of said motor and having a beaded portion including a groove and having a hub portion including, an annular channel, an annular rib extending from said body intermediate said groove and channel; a plurality of slugs each having relatively large heads disposed in said groove, substantially disc shaped tail portions rotatably retained in said channel, and attenuated portions interconnecting said heads and tail portions, the attenuated portion of each of said slugs having a substantially rectilinear face and a notch; an annular shoe positioned against said faces, and spring means for holding said shoe yieldingly against said rectilinear faces whereby the walls of said notches abut said rib to limit displacement of said heads away from said commutator.

2. In a short circuiting device for a motor commutator, an annular shell adapted to be mounted

on the shaft of said motor and having a beaded portion including an annular groove and a hub portion having an annular channel, an annular rib extending from said body intermediate said groove and channel; a plurality of slugs each having relatively large heads disposed in said groove, substantially disc shaped tail portions rotatably retained in said channel, and attenuated portions interconnecting said heads and tail portions, the attenuated portion of each of said slugs having a substantially rectilinear face and a notch; an annular shoe positioned against said faces, and a member having resilient fingers for holding said shoe yieldingly against said rectilinear faces whereby the walls of said notches abut said rib to limit displacement of said heads away from said commutator.

3. In a short circuiting device for a motor commutator, an annular shell adapted to be mounted on the shaft of said motor and having a beaded portion including an annular groove and a hub portion having an annular channel, an annular rib extending from said body intermediate said groove and channel; a plurality of slugs each having relatively large heads disposed in said groove, substantially disc shaped tail portions rotatably retained in said channel, and attenuated portions interconnecting said heads and tail portions, the attenuated portion of each of said slugs having a substantially rectilinear face and a notch; an annular shoe positioned against said faces, and helicoidal spring means for holding said shoe yieldingly against said rectilinear faces whereby the walls of said notches abut said rib to limit displacement of said heads from said commutator.

4. In a short circuiting device for a motor commutator, an annular shell adapted to be mounted on the shaft of said motor and having a beaded portion including an annular groove and a hub portion having an annular channel, an annular rib extending from said body intermediate said groove and channel; a plurality of slugs each having relatively large and substantially disc shaped heads disposed in said groove, substantially disc shaped tail portions rotatably retained in said channel, and attenuated portions interconnecting said heads and tail portions, the attenuated portion of each of said slugs having a substantially rectilinear face and a notch; an annular shoe positioned against said faces, and spring means for holding said shoe yieldingly against said faces whereby the walls of said notches abut said rib to limit displacement of said heads away from said commutator.

5. In a short circuiting device for a motor commutator, an annular shell adapted to be mounted on the shaft of said motor and having a beaded portion including an annular groove and a hub portion having an annular channel, an annular rib extending from said body intermediate said groove and channel; a plurality of slugs each having a relatively large head disposed in said groove, lips extending from said heads, substantially disc shaped tail portions rotatably retained in said channel, and attenuated portions interconnecting said heads and tail portions, the attenuated portion of each of said slugs having a substantially rectilinear face and a notch; an annular shoe positioned against said faces, and spring means for holding said shoe yieldingly against said faces whereby the walls of said notches abut said rib to limit displacement of said heads away from said commutator.

pose said lips out of contact with the latter below a predetermined speed of said shaft.

6. In a short circuiting device for a motor commutator, an annular shell adapted to be mounted on the shaft of said motor and having a beaded portion including an annular groove and a hub portion having an annular channel, an annular rib extending from said body intermediate said groove and channel; a plurality of slugs each having relatively large heads disposed in said groove, substantially disc shaped tail portions rotatably retained in said channel, an attenuated portion interconnecting said heads and tail portions, the attenuated portion of each of said slugs having a substantially rectilinear face and a notch, a ring positioned against said faces, and a member having a plurality of radially arranged and spaced resilient fingers for holding said ring yieldingly against said rectilinear faces whereby the walls of said notches abut said rib to limit displacement of said heads away from said commutator.

7. In a short circuiting device for a motor commutator, an annular shell adapted to be mounted on the shaft of said motor and having a beaded portion including an annular groove and a hub portion having an annular channel, an annular rib extending from said body intermediate said groove and channel; a plurality of slugs each having relatively large heads disposed in said groove, substantially disc shaped tail portions rotatably retained in said channel, an attenuated portion interconnecting said heads and tail portions, the attenuated portion of each of said slugs having a substantially rectilinear face and a notch, an electrically conducting ring positioned against said faces, and a relatively thin spider having a plurality of arcuate and spaced resilient fingers for holding said shoe yieldingly against said rectilinear faces whereby the walls of said notches abut said rib to limit displacement of said heads away from said commutator.

NATHANIEL N. OKUN.
